DESIGN FOR A FLY SWATTER

Adolph F. Shafter, Decatur, Ill., assignor to U. S.
Manufacturing Corporation, Decatur, Ill.

Application October 26, 1935, Serial No. 59,223

Term of patent 14 years

To all whom it may concern:

Be it known that I, Adolph F. Shafter, a citizen of the United States and a resident of Decatur, county of Macon, and State of Illinois, have invented a new, original, and ornamental Design for a Fly Swatter, of which the following is a specification, reference being had to the accompanying drawing, forming part thereof.

In the drawing—

The figure is an elevational view of a fly swat-

ter showing my new design, part of the handle being broken away for convenience of illustration. The side of the fly swatter not shown is substantially the same in appearance as the side which is shown in the drawing.

I claim:

The ornamental design for a fly swatter as shown and described.

ADOLPH F. SHAFTER.
